MICROSCOPE BASE OR SIMILAR ARTICLE

Paul A. Hoogesteger, Penfield, and Edwin A. Speaker,
Brockport, N.Y., assignors to Bausch & Lomb Incorporated,
Rochester, N.Y.

Filed Oct. 10, 1975, Ser. No. 621,431

Term of patent 14 years

Int. Cl. D16—06

U.S. Cl. D16—57

FIG. 1

FIG. 2

FIG. 3

FIG. 4

FIG. 7

FIG. 1 is a top plan view of a base for a microscope showing our new design;

FIG. 2 is a left side elevation thereof;

FIG. 3 is a left rear perspective thereof;

FIG. 4 is a left front perspective thereof;

FIG. 5 is a left front perspective of a modified embodiment of the microscope base shown in FIGS. 1-4;

FIG. 6 is a right front perspective thereof; and

FIG. 7 is a right rear perspective thereof.

We claim:

The ornamental design for a microscope base or similar article, substantially as shown and described.
